UNITED STATES PATENT OFFICE

2,678,028

EXPANSION ENGINE

Win W. Paget, Michigan City, Ind., assignor to
 Joy Manufacturing Company, Pittsburgh, Pa.,
 a corporation of Pennsylvania

Application June 4, 1948, Serial No. 31,017

12 Claims. (Cl. 121—117)

1

This invention relates to expansion engines, that is to engines employed for the purpose of removing energy from a fluid under pressure and thereby reducing the temperature thereof. Such engines are particularly useful in connection with oxygen producing apparatus, but they are also useful with refrigerating machines and other apparatus where it is desired to change the condition of a fluid under pressure by expending some of its energy through the doing of work in an expansion engine.

The principal objects of the invention are to provide an improved expansion engine which is designed in such a manner as to insure a smooth and efficient operation at low temperatures, for example, temperatures at and below those of liquid air; and which embodies improved means for changing the point of cutoff thereof whereby the same may be used, for example, in oxygen producing apparatus, in the production of oxygen at a relatively low pressure, as on the order of 50 pounds gauge, or at a relatively higher pressure as, for example, 2000 pounds per square inch, for cylinder charging. A further and more particular object is to provide an expansion engine having an improved adjustable cutoff mechanism which may be fluid actuated to effect a change from operation with relatively early cutoff to operation with cutoff at a point much later in the stroke. Further objects of the invention and advantages thereof will appear in the course of the following description.

In accordance with the present invention, my expansion engine is of the single acting type, and is equipped with a cylinder and reciprocating piston, with improved actuating means for said piston, and with cam actuated admission and exhaust valves, with each of said valves movable to open position by a cam actuating means, and with the admission valve having associated with it a plurality of cam following rollers, one or more of which may be had in operative relation with an associated cam for providing for different points of cutoff.

Referring to the accompanying drawings, wherein I have shown what is now considered a preferred embodiment of the invention,

Fig. 1 is a side elevational view of an illustrative embodiment of my improved expansion engine, parts being broken away to show details of drive.

Fig. 2 is a vertical section through the lower end of the expansion engine, the section being taken on the planes of the line 2—2 of Fig. 1, but enlarged.

2

Figs. 3 and 3A together provide a vertical axial section through the upper end of the expansion engine, the section being taken on the plane of the line 3—3 of Fig. 1, but enlarged.

5 Fig. 4 is a vertical section on the planes of the line 4—4 of Fig. 2, showing details of construction, and being on a smaller scale.

Fig. 5 is a detail section on the planes of the section line 5—5 of Fig. 2, and on a smaller scale.

10 Fig. 6 is a detail section on the planes of the line 6—6 of Fig. 2, and on a smaller scale.

Figs. 7 and 8 are further detail sections, respectively on the planes of the lines 5—5 and 6—6, showing parts in different operating positions.

15 Fig. 9 is a detail sectional view showing the construction of the pressure fluid operated device for effecting a change in the point of cutoff.

Fig. 10 is a detail sectional view, with parts broken away, and on the plane of Fig. 5, showing 20 a cam control detail, but on a scale larger than that of Fig. 5.

Fig. 11 is a detail sectional view on the plane of Fig. 5, showing parts in different relations to each other.

25 The expansion engine E, as shown in Fig. 1, comprises a section 1 constituting a cylinder; a section 2, which comprises the admission and exhaust valve assembly; a section 3, providing space for thermal insulation, and in which the greater part of the valve assembly is enclosed; a section 4, in which are packing means; and a section 5, which constitutes a crankcase and which houses a crosshead or slide to which motion is transmitted from a crankshaft and which transmits motion to the piston as hereinafter described, and which crankcase also houses improved mechanism for actuating the admission and exhaust valves.

30 One end of the cylinder section 1 (see Fig. 3) is provided with a head 11 having a breather passage 12. The top of the head 11 supports a liquid oxygen pump 13 comprising a cylinder 14 jacketed at 15 and containing a piston 16 adapted to be moved upon its suction strokes by 35 a spring 17, and to be engaged and forced upon its pumping strokes by a surface 18 on piston 19 of the expansion engine, which last piston is reciprocable in the bore 20 of the cylinder 1. The head 21 of the liquid oxygen pump cylinder contains suitable admission and discharge valves, 22 and 23 respectively, and means for moving the piston 16 of the liquid oxygen pump to a position in which it will not be engaged and actuated by the piston 19 is provided as at 24.

55 The piston 19 has a head 25 and an elongated

skirt portion 26. The portion of the expansion engine cylinder below the head 25 constitutes the bottom of a working chamber, or a clearance, into which fluid is admitted to do work on the piston during its upward stroke; and from the working chamber fluid is discharged during the downward strokes of the piston 19. The piston and cylinder are desirably formed from the same wear-resistant metal, the alloy sold under the trade name "Nitralloy" having been found to give superior results when hardened, ground and polished so that the diametrical clearance between the piston and cylinder is between .0003 inch and .0010 inch for a piston having a diameter of two inches. The periphery of the piston may be grooved, if desired, to minimize leakage and to promote centering of the piston in the cylinder.

The head of the piston 19 is formed with a central recess 28 which receives with clearance the flanged head 29 of a flexible piston-rod 30, and a member 31, held in position by screws 32, has an opening 33, through which the piston rod 30 extends; and the member 31 anchors the flanged end of the connecting or piston rod to the piston. Thus the necessary freedom for slight angular and slight bodily relative movements, to prevent lateral stresses, is secured. The piston rod will be observed shortly to transmit tension or pull, but not thrust.

The valve assembly 2 has a circular plate portion 35 fitting against the lower end of the cylinder 1 and formed with an admission port 36 and an exhaust port 37 and a central opening 38 through which the piston rod 30 reciprocates. The plate portion 35 is a part of an admission and exhaust chamber providing casing 39. Beneath the casing 39 is a valve spring housing 40, which may be an aluminum casting and include a pair of depending socket-like casings 41 and 42 registering with the ports 36 and 37. The casing 39 is provided with admission and exhaust chambers 43 and 44, for connection with supply and discharge lines not shown, and admission and exhaust valves 45 and 46 are reciprocable in their respective chambers, and each is movable downwardly against the action of a suitable spring (47 associated with the valve 45 and 48 associated with the valve 46) by improved actuating and controlling means shortly to be described. The lower ends of the casings 41 and 42 are provided with guide bushings 49 and 50 within which there are guided flexible pull rods 51 and 52, which are suitably connected at their upper ends to the valves 45 and 46. The guide bushings 49 and 50, and a corresponding guide bushing 53 for the piston rod, each have projecting bosses to which tubular casings 54, 55 and 56 are soldered. The guide bushing 53 also has an opposite projection secured in a bore 57 in the valve spring housing 40. Within the bore 57 there are suitable guide bushings 58, surrounding the piston rod, and other bushings 59, 60 and 61 surround the valve and piston rods and are spring held, as at 63 in position.

Within the section 4 extend glands 64, 65 and 66 associated with the valve and piston rods, and glands 67, 68 and 69 associated with the casings 54, 55 and 56.

The valve rods are connected to guided end members 71 and 72 adapted to be pulled, to open the valves, by the end portions 73 and 74 of bell crank levers 75 and 76, later more fully described.

The crankcase section 5 of the expansion engine includes a crankcase portion 80 providing a sup-

port 81 for one bearing 82 of a crankshaft 83, a head portion 84 supporting another crankshaft bearing 85, and a gear casing portion 86, housing spur driving gearing 87 and secured as shown to the crankcase 88 of a compressor 89 which supplies compressed air to the oxygen generator of which the expansion engine forms a part. The spur gearing may desirably include a driven pinion 90 suitably secured to the crankshaft (or an extension of the crankshaft) of the compressor.

The crankshaft 83 is rotatably supported by the bearings 82 and 85, and has a crankpin 94 connected by a connecting rod 95 with a tubular crosshead 96 having heads 97 and 98 connected by a trough-like portion 99 and guided respectively in cylindrical guideways 100 and 101. The lower head 98 is constructed similarly to a trunk piston and may be considered to be a piston, and carries a wrist pin 102 to which the lower end of the connecting rod 95 is pivotally connected. A breather conduit B extends from beneath the piston 98 to a point in the crankcase above the uppermost position of the piston 98. The upper head 97 has a central boss 103 in which there is rigidly fixed a reduced lower end portion 104 of a connecting element 105 fixed to the lower end of the piston rod 30. The head 97 is traversed by openings 106, 107 in which the lower ends of members 71 and 72 and their guides 108 and 109 may extend in the various positions of the crosshead 96. The axis of rotation of the crankshaft 83 will be noted to be laterally offset from the line of reciprocation of the axis of the piston rod 30.

Bell crank levers 75 and 76 are mentioned above. The bell crank lever 75 controls admission and cutoff; the bell crank lever 76, release and compression. The bell crank lever 76 and the bell crank lever 75 are both journaled on sleeve bearings 110 on a fixed cross shaft 111 extending through the upper portion of the crankcase section 5. Bell crank lever 76 has an arm 112 substantially at right angles to another arm 113 on which the end portion 74 is carried. A cam 114 is fixed to the crankshaft 83 and has a surface 115 adapted to cooperate with a roller 116 rotatably mounted on the lower end of the arm 112. A spring 117 acts between the arm 112 and an abutment 118 on another cover plate 119 on the crankcase section 5, and maintains the roller in engagement with the cam 114, and when the roller actuating surface 115 is not in contact with the roller 116, the spring 117 moves the end 74 of the bell crank 76 upwardly and allows the spring 48 to close the exhaust valve.

As above noted, the bell crank 75 which controls the movements of the admission valve 45 is supported for oscillation on the shaft 111. This structure is somewhat more complex than that of the bell crank 76, and it has not only an arm 123 similar to the arm 113, and also an arm 124 which carries a roller 126 rotatably mounted thereon; but the arm 124 has an outwardly projecting boss 127 which pivotally supports at 128 another bell crank lever 129 including an upwardly extending arm 130 and a downwardly inclined arm 131. The arm 131 carries at its free end a rotatable cam follower roller 132 whose position with respect to the axis of the crankshaft can be controlled by an adjustable stop screw 133 extending through the arm 131 and engageable with a surface 134 on the boss 127, and by cylinder and piston mechanism 140 which includes a cylinder 141 carried by the vertical arm 130 and having a bore 142 in which a piston

5

143 is received, this piston having a stem or boss 144 adapted to engage a surface 145 stationary with the arm 124 of the bell crank 15; and upon the admission of fluid to the bore 142 through a conduit 146, the cylinder member 141 is adapted to be moved away from the upper end of the arm 124 and thus to swing the second bell crank relative to the bell crank 15 and move the arm 131 counterclockwise in Figs. 4, 5, 7, 10 and 11 until the end of the adjustable screw 133 engages the surface 134.

Fig. 11 shows that at this time the roller 132 will be positioned for engagement by a cam portion 148 of a cam member 149 carried by the crankshaft 83 and controlling admission and cut-off. It will be observed that the spacing of the cam rollers 126 and 132 and the length of the cam projection 148 are such that with the particular proportions of this apparatus, cutoff is made approximately twice as late in the stroke when the roller 132 is moved into cooperative relation with the cam. A spring 150 acts against a surface 151 on the bell crank 129, and another surface 152 on the cover 119. This spring normally maintains the bell crank 75 in such a position that the valve 45 may be seated except when the cam portion 148 is cooperating with one of the rollers 126 or 132.

Fig. 5 shows the position of the parts just as admission is about to take place, noting that the direction of rotation of the crankshaft is counter-clockwise in this figure. Admission is taking place with the parts in the position shown in Fig. 7. With the parts in this position it will be evident that the period of admission is about one-half completed. In the position of the parts shown in Fig. 11, it will be observed that admission has been taking place nearly one and one-half times as long as the full period of admission when the roller 132 is not cooperating with the cam.

It will be apparent that notwithstanding the fact that the expansion engine will be covered thoroughly with insulation in use, there is provided means whereby the cutoff of the engine may be very easily and quickly altered merely by supplying fluid to and venting fluid from the conduit 146, which will desirably be a flexible conduit, at least between its point of ingress to the interior of the crankcase and its point of connection to the movable bell crank mechanism. It will be evident that the construction is simple, that the same spring positions the main bell crank and the auxiliary bell crank when these are not being engaged and actuated by the cam, that the parts are simple and effective and positive in operation, that by reason of the construction of the crosshead and its guides there will be no possible lateral flexure of the flexible piston rod, and that all of the parts of the reciprocating system may be made quite light. Other objects and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

6

der, a crankcase, means for supporting said cylinder on said crankcase, a crankshaft in said crankcase, a crosshead guided in said crankcase for reciprocation along a path extending in the same direction as the path of reciprocation of said piston and having an end nearer said cylinder and an end remote from said cylinder, and said crankshaft having its axis of rotation between the ends of the path of reciprocation of said crosshead, a connection between said crosshead, at the end of the latter nearer said cylinder, with said piston, and a connection between said crankshaft and said crosshead at the end of the latter remote from said cylinder, said cylinder having distributing valve devices associated therewith having stems extending through the end of the crosshead nearer said cylinder, and valve operating means actuated by said crankshaft and extending transversely of said crosshead and between the ends of the latter into cooperative relation with said valve stems.

2. In combination, in an expansion engine, a cylinder, a piston reciprocable within said cylinder, a crankcase, means for supporting said cylinder on said crankcase, a crankshaft in said crankcase, a generally cylindrical crosshead guided in said crankcase for reciprocation along a path extending in the same direction as the path of reciprocation of said piston and having an end nearer said cylinder and an end remote from said cylinder, said crankshaft having its axis of rotation between the ends of the path of reciprocation of said crosshead, a connection between said crosshead, at the end of the latter nearer said cylinder, with said piston, and a connection between said crankshaft and said crosshead at the end of the latter remote from said cylinder, said cylinder having valve devices associated therewith having stems extending through the end of the crosshead nearer said cylinder, said crosshead having one side thereof formed with an opening therethrough, and valve operating means actuated by said crankshaft and including levers pivoted on said crankcase and extending through said opening into cooperative relation with said valve stems.

3. In combination, in an expansion engine, a cylinder, a piston reciprocable within said cylinder, a crankcase, means for supporting said cylinder on said crankcase, a crankshaft in said crankcase, a crosshead guided in said crankcase for reciprocation along a path extending in the same direction as the path of reciprocation of said piston, said crosshead elongated in the direction in which its path extends and having one end between said cylinder and said crankshaft and its other end at the opposite side of said crankshaft from said cylinder, a connection between said crosshead, at the end of the latter nearer said cylinder, with said piston, and a connection between said crankshaft and said crosshead at the end of the latter more remote from said cylinder, said cylinder having distributing valve devices associated therewith having stems extending through the end of the crosshead nearer said cylinder, and valve operating means including bell cranks pivoted on axes adjacent the cylinder-supporting end of said crankcase and having arms extending laterally of said crosshead, between the ends of the latter, into cooperative relation with said stems and further having arms extending towards said crankshaft, and said crankshaft having cams thereon cooperating with said arms.

mission and cut-off valve of an expansion engine having a crankshaft and a valve pulled from its seat to effect admission and oppositely moving to effect cut-off, a valve operating rod traction on which effects valve opening, and means actuated by said crankshaft for pulling said valve actuating rod in a valve opening direction including a cam moving with the crankshaft and two cam follower rolls each cooperatively engageable with said cam, said two cam follower rolls having means for supporting them for turning on relatively laterally offset axes, one of which is movable relative to the other to move the cam follower roll that rotates thereon selectively into positions in one of which it is maintained out of engageability by said cam as the latter moves with the crank shaft.

5. For actuating and controlling the fluid admission and cut-off valve of an expansion engine having a crankshaft and a valve to effect admission and cut-off, a valve operating rod traction on which effects valve opening, and means actuated by said crankshaft for pulling said valve operating rod in a valve opening direction including a cam actuated by the crankshaft and two cam follower rolls for said valve, and means for rendering one or both of said cam follower rolls effective in the control of said valve including means for moving one of said rolls relative to the other and to said cam to position it for engagement by the latter or in another position in which it is out of the range of cam movement.

6. In combination, in an expansion engine having a valve controlling admission and cutoff and a rotating shaft, means for controlling the movements of said valve including a cam rotating with said shaft, a roller actuated by said cam whenever said expansion engine is running and adapted to effect opening of said valve device and to control the closing thereof to effect cutoff at a predetermined point in the working stroke of the expansion engine, another roller mounted for movement with respect to the first roller into and out of cam-engaging position, and means for selectively bringing it into engagement with said cam to extend the period of admission and out of cam engagement to leave control of the period of admission to the first roller.

7. In combination, in an expansion engine having a valve controlling admission and cutoff and a rotating shaft, means for controlling the movements of said valve including a cam rotating with said shaft, a roller actuated by said cam whenever said expansion engine is running and adapted to effect opening of said valve and to control the closing thereof to effect cutoff at a predetermined point in the working stroke of the expansion engine, another roller movably mounted with respect to the first roller and having its axis of revolution offset from the axis of revolution of said first roller and supported for movement into and out of cam-engaging position, and means for selectively bringing said second roller into operative relation with said cam, to extend the period of admission, and moving it to a position in which it is out of the path of said cam, said second roller positionable with respect to the first roller, in cam engaging position, with its center at substantially the same distance from the center of said first roller as the effective length of the cam.

8. In an expansion engine, in combination, a valve for controlling admission and cut-off, and means for controlling the movements of said valve to provide different predetermined periods

of admission including a cam and a lever having a portion movable to effect valve opening and having a pivot and having a portion carrying a roller engageable with the cam, a second lever pivotally supported on the first lever and carrying another roller movable relative to the first roller between positions in which it is uncontacted by said cam or engageable by the latter, means for swinging both of said levers about the pivot of said first lever, and means for swinging the second lever relative to the first to control the position of the roller carried by said second lever.

9. In an expansion engine, in combination, a valve for controlling admission and cut-off and means for controlling the movements of said valve to provide different predetermined periods of admission including a cam and a lever having a portion movable to effect valve opening and having a pivot and having a portion carrying a roller engageable with the cam, a second lever pivotally supported on the first lever and at one side of its pivot carrying another roller movable relative to the first roller between positions in which it is uncontacted by said cam or engageable by the latter, said second lever also having a portion at the opposite side of its pivot from said second roller, means for swinging both of said levers about the pivot of said first lever, and means for swinging the second lever relative to the first to control the position of the roller carried by the second lever, said means for swinging both of said levers including a spring yieldingly pressing the portion of said second lever at the opposite side of its pivot from its roller, towards the other lever.

10. In an expansion engine, in combination, a valve for controlling admission and cut-off, and means for controlling the movements of said valve to provide different predetermined periods of admission including a cam and a lever having a portion movable to effect valve opening and having a pivot and having a portion carrying a roller engageable with the cam, a second lever pivotally supported on the first lever and carrying another roller movable relative to the first roller between positions in which it is uncontacted by said cam or engageable by the latter, means for swinging both of said levers about the pivot of said first lever, and means for swinging the second lever relative to the first to control the position of the roller carried by the second lever, said means for swinging the second lever including cylinder and piston mechanism at the end of the second lever remote from its roller.

11. In an expansion engine, in combination, a valve for controlling admission and cut-off, and means for controlling the movements of said admission valve to provide different predetermined periods of admission including a cam and a lever having a portion movable to effect valve opening and having a pivot and having a portion carrying a roller engageable with the cam, a second lever pivotally supported on the first lever and carrying another roller movable relative to the first roller between positions in which it is uncontacted by said cam or engageable by the latter, means for swinging both of said levers about the pivot of said first lever, and means for swinging the second lever relative to the first to control the position of the roller carried by the second lever, said means for swinging the second lever including cylinder and piston mechanism comprising a cylinder carried by the second lever at the end of the latter remote from its roller,

a piston in the cylinder and having a portion engageable with a portion of the first mentioned lever, and means for supplying and venting fluid relative to the cylinder.

12. In an expansion engine having a crank shaft and a valve device for controlling admission and cut-off, mechanism actuated by said crankshaft for pulling said valve device in an opening direction including a crank shaft rotated cam and two cam follower rolls, and means including pivotally connected, relatively adjustable cam follower roll supporting levers for rendering one of said last mentioned cam follower rolls continuously effective in the control of said valve device and the other only at will.
